ICE FISHING SHANTY

Roger J. Chaponis, 1021 Dyer Lake Road,
Traverse City, Mich. 49684

Filed May 18, 1973, Ser. No. 361,474

Term of patent 14 years

Int. Cl. D25—99

U.S. Cl. D13—1 L

FIG. 1.

FIG. 2.

FIG. 3.

FIG. 4.

FIG. 5.

FIG. 6.

FIG. 1 is a perspective view of an ice fishing shanty embodying the design of my invention;

FIG. 2 is a front elevational view of the ice fishing shanty;

FIG. 3 is a side elevational view of the ice fishing shanty;

FIG. 4 is a side elevational view of the ice fishing shanty from the side opposite the side shown in FIG. 3;

FIG. 5 is a rear view of the ice fishing shanty;

FIG. 6 is a top plan view of the ice fishing shanty.

I claim:

The ornamental design for an ice fishing shanty, as shown.
